The ornamental design for a handle, as shown and described.

DESCRIPTION

FIG. 1 is a perspective view of the handle according to the present design;

FIG. 2 is a top plan view of the handle shown in FIG. 1, the bottom view of the handle being a mirror image;

FIG. 3 is a front elevational view of the handle shown in FIG. 1;

FIG. 4 is a back elevational view of the handle shown in FIG. 1;

FIG. 5 is a side elevational view of the handle shown in FIG. 1 looking from the right end of the drawing;

FIG. 6 is a side elevational view of the handle shown in FIG. 1 looking from the left end of the drawing;

FIG. 7 is a back elevational view of a second embodiment of the handle shown in FIG. 1, the only difference being the configuration of the inner surface of the handle; and,

FIG. 8 is a sectional view taken in the direction of the arrows on line 8—8 of the handle shown in FIG. 7.
